UNITED STATES PATENT OFFICE.

CALVIN L. WESER, OF NEW YORK, N. Y.

PEDAL-ACTION FOR PIANO-FORTES.

SPECIFICATION forming part of Letters Patent No. 448,308, dated March 17, 1891.

Application filed August 13, 1890. Serial No. 361,920½. (No model.)

To all whom it may concern:

Be it known that I, CALVIN L. WESER, a citizen of the United States, residing in New York city, in the county and State of New York, have invented certain new and useful Improvements in Pedal-Actions for Piano-Fortes, of which the following is a specification.

This invention relates, in part, to improvements upon the construction of pedal-action shown in my patent, No. 422,477, dated March 4, 1890.

It also relates, in part, to means for holding the soft or piano stop applied without the necessity of keeping the foot pressed upon the soft pedal, this being often desirable for the purposes of practice. This feature is known in the piano trade as a "harp-pedal."

Figure 1 of the accompanying drawings is a front elevation of part of the pedal mechanism constructed according to my invention. Fig. 2 is a plan thereof. Fig. 3 is a vertical section thereof on the line 3 3 in Fig. 2. Fig. 4 is a similar section showing the parts in a different position. Fig. 5 is a front elevation on a smaller scale, showing the entire length of the tilting bars or rock-shafts and their connection with the upright action-rods. Fig. 6 is a plan thereof. Fig. 7 is a transverse section thereof on the line 7 7 in Fig. 5. Fig. 8 is an enlarged fragmentary detail view showing the connection between the tilting bar and the upright action-rod.

The harp-pedal attachment is omitted from Figs. 5, 6, and 7.

Referring to the drawings, A and A' are the tilting bars or rock-shafts extending longitudinally of the case, and connected, respectively, with the pedal-levers B and B' of the soft and loud pedals or pedal-feet w and w'. The pedal-levers are fastened rigidly to the bars or shafts by set-screws b b', respectively, or in any other suitable manner. The bars or shafts A and A' are mounted in suitable bearings, so as to be free to oscillate as the pedals are depressed, either by having their opposite ends entered in holes X X and X' X', respectively, in the wooden framing of the piano, as shown in Figs. 5 and 6, these holes being suitably bushed with felt or other soft material for deadening the noise, or the shafts are journaled in the manner shown in Figs.

1 and 2, which is the preferred construction. The ends of the shafts are screw-threaded, and on each is tightly screwed a metal thimble or bushing g, having a flange at one end and locked by a flange or nut g', tightly screwed against it, at the other end. The bushing thus fixed around the shaft turns loosely in a bearing of felt or other soft material h, placed in a hole in the supporting-frame. The flanges g g' receive the end-thrust. Both ends are preferably of this construction, and the shafts are also, by preference, supported between their ends by being passed through holes in a bearing-frame X'', arranged just to the left of the pedals, as shown in Figs. 1 and 2, the holes in this frame being bushed with felt.

The bars or shafts A A' have the same function as the tilting bars b b', respectively, in my said former patent. I formerly constructed these bars of wood with metal pivot-pins in their opposite ends. I find it preferable to make them of metal rod, as shown in the accompanying drawings. In my former patent a single spring was interposed between the two wooden bars to impart to them the requisite tension for pressing up the pedals. I now apply this spring to the pedal-levers B B' instead of to the bars. The spring (lettered c) is preferably made of coiled wire with one end entered into a socket or hole in a lug i in the rear of the pedal-lever B, and the other end taking under and exerting an upward tension against a hooked lug or arm i' on the other pedal-lever B'. Its tension is hence upwardly against the lug i' and downwardly against the lug i, and these lugs being on opposite sides of the pivotal axes the effect is to impart to both pedal-feet an upward tension sufficient to lift them. The effect of this tension is also to take up any wear or lost motion in the bearings of the shafts.

In my former patent the connection between the tilting bars and the action-rods was effected by forming the bars with laterally-projecting arms into sockets in which the ends of the rods entered. I have substituted this construction by the one shown best in Figs. 5 to 8. The bars or shafts A A' are bent at or near the left-hand end to form cranks L L', respectively. These cranks are formed,

preferably, as a **U**-shaped lateral bend in the shaft or bar. The outer portion of each crank is extended parallel with the shaft or bar to form a crank-wrist, (lettered *m* in Fig. 8.) The action-rods *J J'*, which are arranged vertically and extend upward for engaging the pianissimo and forte stop mechanisms, respectively, are formed each with a notch *p* in its lower end, as shown in Fig. 8, which is forced down over the crank-wrist *m*, and is formed with a cylindrical portion which embraces the crank-wrist. The notch *p* is made slightly narrower than the wrist, so that some force is required to enter the wrist, it being necessary to spring open this portion of the notch which the wooden rod by reason of its elasticity admits of. As the thrust transmitted through the crank is always upwardly, there is no tendency to draw the crank-wrist down through the notch or in any way disturb the relation of the parts. The forte-action rod *J'* is guided above its lower end by a link *P*, one end of which is pivoted at *T* to the case, and the other end of which is pivoted at *T'* to the rod, as shown in Figs. 6 and 7.

My improved construction of pedal-action thus described is very simple to construct, involves the minimum of pieces to unite, and is free from liability to get out of order or give forth any rattling or squeaking noises in use.

I will now describe how by means of my invention I provide for the application of a harp-pedal or for the continuous holding of the soft or piano pedal in action. The pedal-levers *B* and *B'* are spread apart slightly, and between them is placed an additional lever *D*, terminating in a pedal-foot *d*. So long as this foot *d* is not pressed down, the soft and loud pedals *w* and *w'* may be used in the ordinary manner. The pressing down of this pedal *d*, however, carries down with it the soft pedal *w* to somewhat less than the full extent of its movement and holds it down. While thus held down the piano may be played like any ordinary instrument and the forte pedal *w'* may be used in the normal manner. When it is desired to discontinue the action of the harp-stop, the operator will press on the soft pedal *w*, throwing it down to its extreme movement, whereupon the pedal *d* will fly up, being disengaged from the soft pedal, so that when the soft pedal is released it returns to its normal position. Thus to apply the harp-pedal the operator depresses the pedal *d*, and to release it he depresses the pedal *w*.

The pedal-lever *D* may be pivoted on any suitable axis, and is most conveniently formed with eyes *q q*, which are slipped over the shaft *A'*, in order that the lever may be pivoted to this shaft. Felts are interposed to render the movement noiseless, and collars *a a* are fastened on the shaft by set-screws to prevent longitudinal displacement of the lever. A spring *C* is connected at one end to the lever and at the other end to the framing, in order

to impart an upward tension to the lever to tilt its pedal *d* upwardly. The lever *D* is preferably made forked or **Y**-shaped, and in the bifurcation is pivoted a roller *f*, faced with rubber or other soft or noiseless material. The tilting bar or shaft *A* is fastened rigidly by a set-screw to an arm *E*, which in the normal positions of the parts extends in a curve downwardly and forwardly and terminates directly beneath the roller *f*, as shown in Fig. 3. It is short enough and the positions of the axes of the shafts *A* and *A'* and roller *f* are so arranged relatively that by pressing down the lever *D* the roller *f* in its downward movement depresses the arm *E* and rolls over the end thereof, remaining when the lever *D* is fully depressed at rest against the end of the arm *E*. To more securely hold it in this position, this arm is formed with a notch or concave *e*. Since by the tension of the springs *c* and *C* both the arm *E* and the lever *D* tend to rise, the engagement of the roller *f* with the notch *e* prevents this movement and holds them mutually in their lowered position, as shown in Fig. 4. The arm *E*, by its displacement, has carried down the pedal-lever *B* with it, but to an extent less than its extreme downward movement. When it is desired to release the harp-stop, the downward pressure of the pedal-foot *w* depresses the arm *E* sufficiently to cause its notch *e* to release the roller *f*, whereupon the lever *D* is thrust up by its spring *C*. Then upon lifting the foot the pedal-lever *B* and arm *E* return to their normal position, as shown in Fig. 3. In this position it is to be observed that the pressing down of the soft pedal simply moves the arm *E* down and back without interfering with the lever *D*, so that my improved harp-stop device does not in the least interfere with the normal action of the soft pedal. The action of the loud pedal *w'* is unaffected by the harp-stop whether the latter be on or off.

It should be understood that the roller *f* is not necessarily a roller, but is essentially merely a working face or shoulder formed on or carried by the stop-lever *D*. It might be non-rotative, being a mere fixed shoulder thereon, but arranged relatively to the arm *E* in the same position as the roller in order to coact in the same manner with the arm in passing beyond the end thereof and being engaged by its notch *e*. In any case this working face or shoulder whether it be constructed as a rotative roller or otherwise, should be covered or faced with some soft material in order to avoid noise in its operation.

It will be understood that in place of the springs *c C*, or either of them, counter-weights may be used for pressing up the pedals, such counter-weights being well known as equivalents of springs. I have shown in dotted lines in Fig. 4 a counter-weight applied to the pedal-lever *D* to press it upwardly in lieu of the spring *C*, which may be omitted. The counter-weight may be fastened by a set-screw,

so that it may be adjusted toward or from the axial center in order to regulate the tension. Counter-weights thus applied have some practical advantage over a spring in that the pedal 5 makes less noise when released on striking against the cushion which stops it.

I claim as my invention the following described novel features, substantially as hereinbefore specified, namely:

- 10 1. A pedal-action for piano-fortes, consisting of a tilting bar or shaft of metal rod journaled in bearings in the frame-work, so as to be free to oscillate, and bent at or near one end to form a crank, a pedal-lever fastened 15 on said rod to impart oscillation thereto, and an action-rod engaging said crank bend to be pressed upwardly thereby when the rod is oscillated by depressing the pedal.
- 20 2. A pedal-action for piano-fortes, consisting of a tilting bar or shaft of metal rod journaled in bearings in the frame-work, so as to be free to oscillate, and bent at or near one end to form a crank, a pedal-lever fastened 25 on said rod to impart oscillation thereto, and an action-rod formed at its lower end with an open notch terminating in a rounded socket for engaging the wrist portion of said crank bend and adapted to be forced or sprung thereover.
- 30 3. A pedal-action for piano-fortes, consisting of a tilting bar or shaft of metal rod having a pedal-lever fastened on it and provided with journal-bushings screwed on threaded portions of the rod, having opposite flanges 35 for receiving longitudinal thrust, and bearings for said rod embracing said bushings and faced with intervening felt or equivalent soft material.
- 40 4. A pedal-action for piano-fortes, consisting of two tilting bars or shafts of metal rod journaled in bearings in the frame-work, so as to be free to oscillate, two pedal-levers fastened on said rods, and a single intervening spring for pressing the pedals upwardly, 45 fastened at one end to one of the pedal-levers and at the other end to the other pedal-lever, engaging them on relatively opposite sides of the pivotal axes and adapted to exert a pressure against the two levers in opposite directions, whereby each receives the reaction of 50 the thrust imparted to the other.

5. The combination, with a pedal-action for piano-fortes, comprising the soft pedal and the parts operated thereby, of means for retaining the soft pedal applied, consisting of a supplemental stop-pedal and a vibrating arm in connection with the soft pedal, arranged relatively to the stop-pedal to be tilted by the depression thereof, and thereby 60 to press down the soft pedal, and means for holding said stop-pedal down.

6. The combination, with a pedal-action for piano-fortes comprising the soft pedal and the parts operated thereby, of means for retaining the soft pedal applied, consisting of a supplemental stop-pedal and a vibrating

arm in connection with the soft pedal arranged relatively to the stop-pedal to be tilted by the depression thereof, and thereby to press down the soft pedal, and constructed 70 when thus tilted to engage the stop-pedal and hold it down.

7. The combination, with a pedal-action for piano-fortes, comprising the soft pedal and the parts operated thereby, of means for retaining the soft pedal applied, consisting of a supplemental stop-pedal and a vibrating arm in connection with the soft pedal arranged relatively to the stop-pedal to be tilted by the depression thereof, and thereby 75 to press the soft pedal down part way, and constructed when thus tilted to engage the stop-pedal and hold it down, and adapted by its further tilting by the complete depression of the soft pedal to disengage and release the 80 stop-pedal.

8. The combination, with a pedal-action for piano-fortes, comprising the soft pedal, a longitudinal tilting bar or shaft on which it is fastened, and means for pressing it upwardly, of means for retaining the soft pedal applied, consisting of a supplemental stop-pedal having means for pressing it upwardly, and a vibrating arm fixed to the soft-pedal shaft and extending beneath some part of 90 said stop-pedal in order that it shall be engaged and tilted thereby upon the depression of the stop-pedal, and thereby oscillate the soft-pedal shaft.

9. The combination of the soft pedal *w*, its 100 shaft *A*, an arm *E*, fixed to said shaft, and a stop-pedal *D*, normally pressed upwardly and having a roller *f* arranged upon its depression to press down the arm *E*.

10. The combination of the soft pedal *w*, its 105 shaft *A*, an arm *E*, fixed on said shaft, and a stop-pedal *D*, pivoted on an axis in the rear of the shaft, normally pressed upwardly, and having a roller *f* arranged normally above the arm *E*, and adapted upon the depression 110 of the stop-pedal to engage and press down the arm *E*, and arranged relatively to the length of said arm to pass beyond the end thereof and be engaged and held down thereby.

11. The combination of the soft pedal *w*, its 115 shaft *A*, an arm *E*, having a notch or recess in its end, and a stop-pedal *D*, pivoted in the rear of said shaft, normally pressed upwardly, and having a roller *f* arranged relatively to said arm to engage and depress it upon the 120 depression of the stop-pedal and to pass beyond its end and be engaged by the notch therein to hold the stop-pedal down.

In witness whereof I have hereunto signed my name in the presence of two subscribing 125 witnesses.

CALVIN L. WESER.
